UNITED STATES PATENT OFFICE.

HIRAM TYREE, OF NEW YORK, N. Y.

BURIAL-CASE.

1,365,634.

Specification of Letters Patent. Patented Jan. 11, 1921.

Application filed July 16, 1919. Serial No. 311,152.

To all whom it may concern:

Be it known that I, HIRAM TYREE, a citizen of the United States, and residing in the city, county, and State of New York, have 5 invented new and useful Improvements in Burial-Cases, of which the following is a specification.

My invention is adapted for either a casket or as the casket container; it particularly relates, however, to a casket container. The object of my invention is to provide a burial case which, while being substantially imperishable, and adapted to be hermetically sealed, is simple, readily constructed, of 15 great mechanical strength and is readily sealed at the place of interment and with the few facilities usually obtainable at such a place. Another object of my invention is to provide a burial case of pleasing appearance and one in which the contents are 20 visible.

In a general way, the burial case of my invention comprises initially, separate sides, ends, bottom and cover of a brittle vitreous material, with metallic rims or strips along the respective edges thereof. The metallic rims or strips project beyond the edges of the vitreous parts and at assembly adjacent strips are soldered together to provide hermetically sealed joints. If the contents of 30 the case are to be visible, a transparent vitreous material is used. Other details will appear from the following description of an embodiment of my invention.

35 In the accompanying drawing and the following description, I have illustrated and described the best embodiment of my invention of which I am now aware. Figure 1 is a perspective, partly in section, of the burial case of this embodiment of my invention. Fig. 2 is a section of a corner thereof, looking downwardly on the line II—II of Fig. 1. Figs. 3 and 4 show a section through one side and the adjacent parts of the cover and bottom, looking in the direction of the arrows on the line III—III—III of Fig. 1. Fig. 5 is a perspective of the reinforcement and rims shown in other figures embedded in the sides of the case. Fig. 6 is a sectional view of the case of Fig. 1, the carrier being omitted however.

The burial case of this embodiment comprises a cover 1, two sides 2, two ends 3 and the bottom 4. Each of these parts is substantially rectangular in shape and comprises for the most part a slab of a trans-

parent vitreous material whereby the contents of the case are visible. In the edges of the vitreous slab of the cover 1 is embedded a metallic rim or rim members as 60 shown in Figs. 3 and 6. This rim, or each of the rim members, if separate members or sections are used for the different edges, comprises a channel member, the longer leg 7 of which is embedded well within the vitreous material substantially parallel with the faces or upper or lower surfaces of the cover 1. This leg 7 may be provided with barbs 8 to secure a firmer grip in the vitreous material; these barbs may be punched up from the material of the leg 7. The web 9 of the channel or channels which comprise the rim or rims of the cover 1, is so disposed that its exterior face is substantially in the same plane as the exterior edge of the vitreous material adjacent thereto, as appears in Fig. 3; thus the channel rim and the vitreous material provide substantially a single surface for the edge of the cover 1. The shorter leg 10 of the channel rim likewise lies in a 80 surface of the cover 1, that is, in the lower face thereof and its outer surface is substantially in the plane of the lower surface of the vitreous material of the cover 1. As may be observed from Figs. 3 and 6, the leg 85 or legs 10 provide engaging, seating, surfaces of the cover 1, that is, the surfaces which engage with the sides of the case and on which the cover is seated. Each of the sides 2 is likewise provided with a metallic 90 rim about its edges; the sides are further provided with embedded reinforcements. In the instance illustrated the rim members and the reinforcing for each side are comprised in a unitary structure, which is illustrated in 95 Fig. 5. Referring first to Fig. 3, it will be observed that the top and bottom metallic strips or rim members comprise T-shapes. The webs of the T's provide the whole, or substantially the whole, exterior surfaces of 100 the top and bottom edges of the sides 2. The outer flange of the T along the top edge of each side, lies within the respectively adjacent surface of the vitreous material of the side substantially as the flange or leg 105 10 of the channel member lies within the lower face or surface of the cover 1; the outer flange of the T along the lower edge lies in a recess (later referred to again) in the outer surface of the vitreous material 110 and extending the whole length of the side; the central flange of each T member is em-

bedded within the vitreous material of the side. The central flanges may be provided with barbs as illustrated with respect to the leg or flange 7 of the rim of the cover.

5 Along each end of each side 2 there is placed a channel member 12, one leg of which is disposed in a recess (later referred to again) in the outer surface of the vitreous material and extending across the whole end of 10 the side 2; the other leg of the channel member is disposed in the inner surface of the side 2 substantially as the leg 10 is disposed in the inner or lower surface of cover 1. The T and channel members form or 15 provide the surfaces of the sides 2 which engage with the adjacent parts of the case, namely the ends, cover and bottom (see Figs. 2 and 6). The webs of the channel members 12 may be provided with struck-up 20 barbs or projections 12^a more or less encircling wires or rods 12^b embedded in the vitreous material along the ends thereof, to assist in retaining the channel members in the vitreous material. For convenience of 25 manufacture, the two T members and the two channel members 12 may be fixed together into a rectangular structure (Fig. 5), in their relative positions in the finished structure, prior to the molding of the vitreous material thereabout. Also for convenience of manufacture or otherwise, the reinforcements 13 of each side may be fixed to the structure provided by the rim members, as shown in Fig. 5. Preferably and particularly where the sides of the case are 30 made up of a transparent vitreous material whereby the contents of the case are visible, the reinforcement comprises a plurality of vertical bars 13 spaced some distance apart 35 in order to allow as uninterrupted a view of the interior through the sides, as possible. These bars are preferably provided with barbs 14 punched up therefrom, as shown in Fig. 5. These bars are also adapted to receive threaded bolts later referred to, these 40 bolts to be inserted from the interior of the burial case. For this purpose, particularly on account of the thinness of the material of the bars 13, I prefer to provide the bars 13 with threaded sections or studs 15 fixed thereto and projecting therefrom toward the inner surface of the side 2. These sections or studs are of such length as to project just to the inner surface of the sides 2; in addition to their function in the burial case, as 45 later described, these studs may also assist in holding the reinforcement properly spaced with respect to the forms during the molding of the vitreous material. Each end 50 3 of the burial case is quite similar in construction to the cover 1 excepting in the matter of size and proportions and excepting that the webs of the metal channel or channels along those edges of the ends which 55 contact with the sides are disposed in recesses 60 65

(later referred to again) in those edges of the vitreous material and the exposed flanges in the bottom edges lie in similar recesses in the outer surfaces of the ends 3; it is not necessary therefore to further describe the 70 ends 3. The bottom 4 of the case is also quite similar to the cover 1 with the addition of a woven wire reinforcement 19 embedded in the vitreous material of the bottom, excepting that the webs of the channel 75 rims or strips are disposed in recesses in the edges of the bottom (Figs. 3 and 6); it is not necessary to further describe the construction of the bottom 4.

The cover 1, two sides 2, two ends 3, and 80 the bottom 4 are assembled as a box with the sides 2 and ends 3 resting on the upper surface of the bottom 4, as appears in Figs. 3 and 6. The sides 2 are placed between the 85 ends 3 as appears from Fig. 2. It will be observed from Figs. 2, 3 and 6 that the metallic rims or strips provide the engaging or seating surfaces of and between the ends and sides, between the ends and bottom, between the sides and bottom, and between 90 the cover, sides and ends; in other words, metallic surfaces of the sides 2 and ends 3 stand on metallic surfaces of the bottom 4, metallic surfaces of sides 2 abut metallic surfaces of the ends 3, and likewise metallic 95 surfaces of the cover 1 rest on metallic surfaces of the sides and ends 2 and 3. Also by reason of the T and channel construction of these metallic strips, these engaging surfaces are firmly and hermetically fixed to the 100 vitreous material and metallic surfaces are exposed at both sides of each joint. These engaging metallic surfaces of different parts of the case, or rather the exposed adjacent metallic surfaces, are soldered (using that term broadly), as shown at 20, 21, 22, 23 and 24, whereby all the joints of the case are 105 hermetically sealed and are readily and easily hermetically sealed by a simple operation. The joints, excepting those at the 110 cover, may be soldered internally as at 21 and 24, if desired, as well as externally.

Provisions are made for preventing the destruction of the exposed parts of the metallic strips by the weather. As will be seen from Figs. 2, 3 and 6, co-operating recesses (heretofore mentioned) are provided in the exposed edges and surfaces of the sides, ends and bottom 2, 3 and 4 along their mutually engaging edges. It is in these recesses 115 that the respective metallic strips or rims are exposed outside the joints, and it is also within these recesses that the external soldering is done at 20, 22, etc., between the sides, ends and bottom. After the soldering 120 is completed the exposed surfaces of the metallic rims and the soldering thereon are covered with a suitable imperishable material impervious to the weather, that is, one 125 which is incapable of being acted on by the 130

elements or which otherwise restrains access of the elements to the metallic strips and solder. This material is preferably an imperishable impervious plastic material; sodium silicate is an example of the materials that may be used. It will be observed that by reason of the fact that after the application of such a material to the exposed metal parts of the burial case, the case is practically imperishable except through severe blows, since none of its exposed surfaces are subject to destruction or penetration by the elements.

In addition to the natural strength possessed by the case by reason of the particular assembly described, by reason of the soldering, etc., the case is preferably carried and strengthened and the ends and sides further supported, as it were, by the external metallic frame 29. This carrying and end-and-side-supporting frame 29 comprises generally an open frame of box-like configuration, preferably metallic, surrounding the case; it extends below the case to receive the weight thereof and in order that the case may be safely carried through the frame. The frame illustrated comprises a lower rim 31 surrounding the entire lower edge of the case and provided with a horizontal flange 32 and a vertical flange 33 integral therewith. The case rests on the flange 32 and between the flanges 33, and fits more or less tightly therebetween. Extending upwardly from the vertical flange 33 are a plurality of vertical bars 34; and one of these bars in the form of an angle bar extends vertically along each vertical edge of the case (see Fig. 1). Preferably, and especially when the case is made of a transparent vitreous material whereby the contents of the case are visible, a vertical bar 34 is provided along each of the embedded reinforcing bars 13; these vertical bars, both at the corners and along the faces of the case, are of sufficient width to conceal from view the vertical metallic rim strips and the vertical reinforcements 13, whereby a pleasanter and apparently more complete structure results. Certain of the vertical bars 34 are provided with threaded bolts 38 to receive handles 39 by which the frame, and therethrough the case, may be carried. The frame 29 also comprises a horizontal bar 40 surrounding the case at the top thereof. To this bar 40 there is hinged a lip 41 at each side and end of the case, these lips being wide enough to extend some distance over the edges of the cover 1 and both 40 and 41 being wide enough to conceal the metallic rims of the cover and the upper metallic rims of the sides 2.

While the cover 1 is adapted to rest on the sides and ends 2 and 3 and to be carried thereby, I prefer to provide internal cover supporting members 45. These members

are substantially U-shaped pieces, the horizontal web portions of which are of sufficient length to span the interior of the burial case. From the ends of the webs of the members, legs 46 extend downwardly, reaching preferably to and standing on, or reaching substantially to the bottom 3. These members 45 are provided with bolt holes or recesses registering with the threaded studs 15 carried by the reinforcing members 13. When bolts are positioned in these recesses and studs 15, the upper horizontal web members of the cover supports 45 are disposed just high enough to receive all or a part of the weight of the cover 1. These cover supporting means 45 are removed to admit the case contents, and thereafter replaced and bolts seated in the recesses thereof and in the studs 15 just before the case is finally closed by its cover 1.

It will be understood that the sides and ends and bottom of the case may be assembled and soldered and the impervious coating provided over the exposed surfaces of the solder and metallic rim strips, and the whole placed within the carrying and end-and-side-supporting frame 29, at any time prior to use. The cover is placed in position and soldered at 23 after the case has received its contents. Thereafter the lips 41 are turned on their hinges to the positions shown in Fig. 1 for the purposes before indicated. The adjoining edges of the lips 41 may be soldered or otherwise attached if desired to assist in keeping these lips in the desired positions.

I have thus illustrated and described in some detail the best embodiment of my invention of which I am now aware. It will be understood, however, that this embodiment is merely illustrative of my invention and that my invention is not limited thereto, but that my invention which I desire to secure by Letters Patent is set forth in the following claims:

1. A burial case comprising sides, ends and bottom of separate pieces of brittle material, each of said pieces having a metallic rim partially embedded therein and the adjacent rims being soldered together to hermetically seal the joints.

2. A burial case comprising sides, ends and bottom of separate pieces of vitreous material having metallic strips partially inclosed in their edges, the said metallic strips providing the mutually engaging surfaces of the separate pieces and being soldered together to hermetically seal the joints.

3. The burial case of claim 2 characterized by a vitreous cover having a metallic strip or strips at the edge thereof and the sides and ends having metallic strips at the edges thereof which are adjacent the

cover, the adjacent metallic strips of the cover and sides and cover and ends being soldered to provide hermetically sealed joints between said parts.

5. The burial case of claim 2 characterized by an external open frame surrounding said case and supporting said sides and ends.

5. The burial case of claim 2 characterized by an external open frame surrounding said case and extending below the bottom therefor whereby the bottom, sides and ends are carried and the ends and sides are supported.

15. 6. The burial case of claim 2 characterized by the vitreous material of one of said sides being transparent and said side having a reinforcement of a plurality of spaced vertical bars embedded therein.

20. 7. The burial case of claim 6 characterized by an external carrying and end-and-side-supporting frame extending below said bottom and comprising spaced vertical members and a horizontal bar surrounding said case concealing from view the reinforcing bars and the metallic strips.

25. 8. The burial case of claim 2 characterized by the sides having reinforcements of

a plurality of spaced bars, cover supporting members within the case, and means for attaching said cover supporting members to said spaced bars.

30. 9. The burial case of claim 1 characterized by means impervious to the weather covering the soldered joint and parts of the metallic rims remaining exposed after the soldering.

35. 10. The burial case of claim 2 characterized by the case being provided with recesses at the joints between the sides, ends and bottom in which the metallic rims are exposed and soldered, and a plastic impervious to the weather disposed in said recesses protecting said metallic parts from the elements.

40. 11. The burial case of claim 3 characterized by an external carrying and end-and-side supporting frame comprising a horizontal bar surrounding the case at the top thereof, and a lip hinged adjacent said horizontal bar at each side and end of the case to conceal from view the joints at the edges of the cover.

45. In testimony whereof, I have signed this specification.

HIRAM TYREE.
